UNITED STATES PATENT OFFICE.

CONRAD B. MAUER AND HOWARD P. MAUER, OF PHILADELPHIA, PENNSYLVANIA.

SCENERY-FORMING PAPER.

Application filed November 8, 1924. Serial No. 743,639.

Generally stated, this invention relates to 5 scenery-forming paper for Christmas tree garden decorations such as miniature mountain, tunnel, and like scenery and has more especial relation to rendering the same highly fire-resisting in character.

The scenery-forming paper described and claimed in our aforesaid patent has given excellent results in practice. Due to the fact 10 that Christmas trees are frequently illuminated by candles and electric lights; and due further to the fact that numerous electrical devices are frequently used in and around Christmas tree gardens we have found 15 that it is highly desirable that our said scenery-forming paper possess high fire-resisting characteristics.

The leading object of the present invention is to provide scenery-forming paper 20 possessed of high fire-resisting characteristics manufactured in roll form for sale by the yard, which paper is sufficiently pliable to permit shaping by hand to produce miniature mountains, tunnels, and the like without 25 employment of braces, frames, or similar supporting structure.

With this and other objects in view, the invention consists of the novel form of 30 scenery-forming paper as hereinafter described and finally claimed.

The nature, characteristic features and scope of the invention will be more fully understood from the following description taken in connection with the accompanying 35 drawings forming part thereof and in which there is shown a view of a roll of scenery-forming paper embodying features of the invention and illustrating a portion thereof opened to expose the treated surface.

For the purpose of illustrating our invention we have shown in the accompanying drawings one form thereof which is at present preferred by us, since the same has been 40 found in practice to give satisfactory and reliable results, although it is to be understood that the various instrumentalities of which our invention consists can be variously arranged and organized and that our 45 invention is not limited to the precise arrangement and organization of the instrumentalities as herein shown and described.

In the manufacture of scenery-forming paper embodying the present invention we prefer to employ a good grade of tough, pliable paper in rolls of approximately 50

yards and of a width approximating 24 inches, said paper being tinted a relatively dark lead color at the mill. This lead colored paper we decorate with dabs of white paint 60 to represent snow the dabs of red and yellow paint to represent mineral deposits. While still wet the paint is brushed out in varigated wave-like fashion to produce vein-like and other irregular effects. The 65 paper so treated is allowed to dry and is then presented to and passed through a bath or solution of potassium permanganate and sodium silicate. Such solution is of an adhesive nature. We now sprinkle material 70 known as "green moss" and ground mica upon the treated adhesive surface of the paper in an irregular manner. The paper so treated is now permitted to dry, the potassium permanganate assisting in the rapid 75 drying of the treated surface. The paper is now possessed of fire resisting characteristics and experience demonstrates that even when subjected to a high heat it will merely glow and disintegrate instead of bursting 80 into a flame. Our prepared paper is quite pliable which is important since it must stand considerable crumpling or like manipulation. If the paper when treated is possessed of stiff, brittle characteristics it can 85 not be satisfactorily employed for the purpose designed.

The prepared paper is now re-rolled for wholesale distribution and is retailed by the yard. It is possessed of sufficient body so that when crumpled to desired configuration as a miniature mountain, tunnel or the like it is self-supporting. In practice we have found that a bath or solution of approximately eight (8) parts of sodium silicate and one (1) part of potassium permanganate gives excellent results.

While we have described a paper previously tinted a relatively dark lead color we may if desired take a good grade of tough, pliable paper in an untinted condition and 100 coat one entire face thereof with relatively dark lead paint. When pursuing the latter course we have found that best results are obtained by using paint consisting of a lead pigment darkened to a desired shade and 105 mixed with a liquid composed of synthetic gum, petroleum spirits, and a rapid drier. Before the paint has dried sand is sprinkled thereover which in conjunction with the dark colored paint is symbolic of a rough 110 rocky background. While still wet the paper has also sprinkled thereover saw-dust

colored green, moss or equivalent material symbolic of grass. In this condition the painted paper is ready for the previously described bath to render the paper fire-resistant 5 and while wet sprinkle thereover sand, saw-dust colored green, and moss or equivalent material.

In the drawings the background of a roll of paper 1 is designated 2, the dabs of white 10 paint, symbolic of snow, are designated 3 and the dabs of paint symbolic of mineral deposits are designated 4. The white mica sprinkled thereover to provide a glistening effect thus enhancing the imitation of snow 15 is designated 5 and the green moss 6.

It will now be apparent that we have devised a novel and useful construction which embodies the features of advantage enumerated as desirable in the statement of the 20 invention and the above description and while we have in the present instance shown and described the preferred embodiment thereof which has been found in practice to give satisfactory and reliable results, it is to 25 be understood that the same is susceptible of modification in various particulars without departing from the spirit or scope of the invention or sacrificing any of its advantages.

30 Having thus described our invention, what we claim as new and desire to secure by Letters Patent, is:

1. As a new article of manufacture Christ-

mas-tree-garden, scenery formation paper in roll form for sale by the yard consisting of 35 thin, tough sheet paper treated with lead paint to provide a dark background, and also to provide a pliable backing, said background having painted thereon rock, snow, mineral and grass symbols, said paper being 40 fire-resisting in character by reason of a coating of sodium silicate to which has been applied potassium permanganate, the latter serving as a dryer and also which is relatively sticky to accept additional scenery 45 symbols.

2. As a new article of manufacture Christmas-tree-garden, scenery formation paper in roll form for sale by the yard consisting of 50 thin, tough sheet paper treated with lead paint to provide a dark background and also to provide a pliable backing, said background having painted thereon rock, snow, mineral and grass symbols, said paper being 55 fire-resisting in character by reason of a coating of about nine (9) parts of sodium silicate to which has been applied about one (1) part of potassium permanganate the latter serving as a dryer and also which is relatively sticky to accept additional scenery 60 symbols.

In testimony whereof, we have hereunto signed our names.

CONRAD B. MAURER.
HOWARD P. MAURER.
